US0D1018554S

(12) **United States Design Patent** (10) **Patent No.:** **US D1,018,554 S**
(45) **Date of Patent:** **** Mar. 19, 2024**

(54) **DISPLAY SCREEN WITH A GRAPHICAL USER INTERFACE**

(71) Applicant: **Norton (Waterford) Limited**, Waterford (IE)

(72) Inventor: **Xinyu Liu**, Winchester, MA (US)

(73) Assignee: **Norton (Waterford) Limited**, Waterford (IE)

(**) Term: **15 Years**

(21) Appl. No.: **29/732,574**

(22) Filed: **Apr. 24, 2020**

(51) LOC (14) Cl. **14-04**

(52) U.S. Cl.

USPC **D14/485**

(58) **Field of Classification Search**

USPC D14/485-488

CPC G06F 3/048; G06F 3/0481; H04M 1/724-72484

(57) **CLAIM**

The ornamental design for a display screen with a graphical user interface, as shown and described.

DESCRIPTION

The application file contains at least one drawing executed in color. Copies of this patent application publication with a color drawing will be provided by the Office upon request and payment of the necessary fee.

The sole FIGURE is a front view of a display screen with a graphical user interface, showing our new design.

The solid line perimeter shows the display screen and forms a part of the claimed design.
